SHOE LOOP

Friedrich Aufenacker, 13 Kirchbergweg,
Wuppertal-Sonnborn, Germany

Filed Dec. 1, 1965, Ser. No. 8

Term of patent 14 years

(Cl. D2—405)

Fig. 1

Fig. 3

FIG. 1 is a top plan view of a shoe loop showing my new design, a bottom plan view would be identical thereto;

FIG. 2 is a side elevational view; and

FIG. 3 is a sectional view looking in the direction of the arrows III-III.

I claim:

The ornamental design for a shoe loop, as shown and described.
